UNITED STATES PATENT OFFICE.

WILLIAM P. NORRIS, OF SISTERSVILLE, WEST VIRGINIA

AUTOMATIC CUT-OFF FOR TANKS.

1,016,516.

Specification of Letters Patent.

Patented Feb. 6, 1912.

Application filed December 9, 1910. Serial No. 596,514.

To all whom it may concern:

Be it known that I, WILLIAM P. NORRIS, a citizen of the United States of America, and resident of Sistersville, county of Tyler, 5 and State of West Virginia, have invented certain new and useful Improvements in Automatic Cut-Offs for Tanks, of which the following is a specification.

This invention relates to improvements in 10 automatic cut-offs for oil and other tanks, and it consists in the particular construction, arrangement and combination of parts which will hereinafter be fully described.

The primary object of the invention is to 15 provide means whereby the supply of fluid entering or passing from a tank may be automatically cut off at any predetermined level.

A further object is to provide a simple, 20 efficient and inexpensive device for automatically closing the tank against egress of fluid when a predetermined level is reached, and means whereby said tank is automatically closed to prevent overflow when filled.

25 The invention has relation to that class of automatic cut-offs disclosed by United States Letters Patent, No. 882,956, granted to me March 24, 1908, and it contemplates the structural improvement of the mechanism disclosed by said patent.

In describing the invention in detail, reference is herein had to the accompanying drawings forming a part of this specification, in which—

35 Figure 1 is a side elevation of the invention applied to a tank, the latter being shown in vertical section; Fig. 2 is an enlarged vertical section of the invention, a broken portion of the top of a tank being 40 shown; and—Fig. 3 is an enlarged section on the line 3—3, Fig. 1.

Referring to said drawings, in which like designating characters distinguish like parts throughout the several views—1 indicates a 45 tank through the wall of which extends a service pipe 2 through which the tank is both filled and emptied. Mounted upon the inner end of said pipe is the tubular nipple 3 of a valve casing 4. Said casing is provided with a valve seat 5 upon which a vertically movable gate-valve 6 is adapted to seat for closing a port 7 leading from the interior of said casing to said pipe. Said valve seat preferably has an inclined wall 5^a 50 on the side opposite the port 7, and the valve 6 has a correspondingly located and

correspondingly inclined face 6^a as shown, said wall and said face coöperating to seat said valve in a position effectually closing the port 7.

60 The valve 6 is fixed upon the lower end of a vertically-movable rod 8 which extends outward through the top 9 of the tank and bears a weight 10 upon its upper end. A collar 11 adjustably mounted upon the rod 65 8 is normally engaged on its under face by the point 12^a of a lever 12 which is pivotally supported intermediate its ends upon a standard 13 mounted upon the top of the tank, said lever normally maintaining the 70 rod 8 and attached valve 6 in an upraised position, as shown in Fig. 2. Adjustably supported in the end of said lever 12 which is opposite its point 12^a is a removable sleeve 14, preferably rectangular in form, 75 in which is adjustably mounted a vertically-movable rod 15, a set-screw 16 being provided for holding said rod in adjusted position. The rod 15 has a fixed head 26 upon its lower end, and freely movable or slidably 80 upon the body of said rod is a hollow float 17 comprising a cylindrical vessel having a central rod-embracing tube 18, the opposite ends of which project beyond the ends of said vessel. An apertured tubular inlet 19 85 is provided upon the top of the float for a purpose which will presently be explained.

In practice, when it is desired to fill the tank, a collar 20 is adjusted upon the float 90 15 according to the depth of fluid which it is desired attained in the tank, and the valve 5 is opened. When the float has risen with the rising fluid until the upper end of the tube 18 engages said collar 20, the latter begins to rise therewith carrying the rod 95 15 upward and elevating the butt-end of the lever 12 until its point 12^a becomes disengaged from collar 11, when the rod 8 and gate-valve 6 are permitted to drop, the latter assuming its seat and closing the port 7. 100

In removing the fluid from the tank, when said fluid is lowered sufficiently, the lower end of the tube 18 seats upon the head 16 of the rod 15, thus pulling downward upon the rod 15, tilting the lever 12 until its point is withdrawn from engagement from the collar 11, allowing the valve to drop and close port 7. As is obvious, by adjustment of the rod 15, the device may be set 105 for automatically cutting off the discharge of fluid at any predetermined level.

When the valve is open to the admission

- of fluid and the device has not been ad-
justed to close the port at any predeter-
mined point, the tank is nevertheless pre-
vented from overflowing in the following
manner: The float is raised until it reaches
a non-progressive position against the top
of the tank. In this position it will be
filled with fluid through the tubular inlet
19 as the fluid in the tank rises about it.
- 10 The weight of the float will consequently
become such that it will sink upon the head
of the rod 15, carrying the latter downward,
and, through the intermediate mechanism,
effecting the closing of port 7.
- 15 A suitable strainer 21 is provided where-
by foreign substances or matter is prevented
from entering the tank with the fluid. Said
strainer is carried upon the lower end of
20 a tube 22 through which the valve rod 8
is extended, and it seats in the upper end
of the valve casing 4. When it is desired
25 to remove the strainer for any purpose, as
for cleaning, a guide-plate 23 is removed
from its supports, and said tube 22 and at-
tached strainer are raised bodily through
30 a lid-closed opening 24 provided in the top
of the tank. A lid-closed opening 25 is also
provided in the top of the tank for permitting
of the removal of the float from the
tank.

Having thus described my invention, what
I claim as new, and desire to secure by Let-
ters Patent, is—

1. The combination with a tank having a
35 service-pipe extended thereinto, of a valve-
casing connected to said pipe, a valve-seat
in said casing, a valve, a rod from which
said valve is suspended, a lever pivotally
mounted over said tank, adjustable means
whereby said rod is suspended from the
point of said lever, a straining element
seated in the top of said valve casing, a
tube connected to said straining element and
loosely embracing the valve-rod, said tube
extending to the top of the tank, said tank-
top having a lid-closed opening through
which said tube and straining element may
be removed, a float-rod adjustably mounted
upon the butt-end of said lever and extend-
ing into the tank, and a float slideable upon
said float-rod.

2. The combination with a tank having a
service-pipe extended thereinto, of a valve-
casing connected to said pipe, a valve-seat
in said casing, a valve, a rod from which
said valve is suspended, a lever pivotally
mounted over said tank, adjustable means
whereby said rod is suspended from the
point of said lever, a float-rod adjustably
mounted upon the opposite end of said lever
and extending into the tank, a hollow float
slideable on said float-rod within the tank,
and removable means for preventing foreign
matter from entering the tank with the
fluid, said means comprising a strainer
seated within the top of said valve-casing,
and a tube to which said strainer is con-
nected, said tube extending to the top of
the tank.

2. The combination with a tank having a
service-pipe extended thereinto, of a valve-
casing connected to said pipe, a valve-seat
in said casing, a valve, a rod from which
said valve is suspended, a lever pivotally
mounted over said tank, adjustable means
whereby said rod is suspended from the
point of said lever, a float-rod adjustably
mounted upon the opposite end of said lever
and extending into the tank, a hollow float
slideable on said float-rod within the tank,
and removable means for preventing foreign
matter from entering the tank with the
fluid, said means comprising a strainer
seated within the top of said valve-casing,
and a tube to which said strainer is con-
nected, said tube extending to the top of
the tank.

In testimony whereof I affix my signature
in presence of two subscribing wit-
nesses.

WILLIAM P. NORRIS.
